(57) **CLAIM**

The ornamental design for the scent dispensing fishing lure, as shown and described.

DESCRIPTION

FIG. 1 is a perspective view of a scent dispenser fishing lure showing my new design;

FIG. 2 is a side elevation view as seen from the right in FIG. 1;

FIG. 3 is a side elevation thereof as seen from left in FIG. 1;

FIG. 4 is a top plan view thereof;

FIG. 5 is a bottom plan view thereof;

FIG. 6 is a front elevation view thereof;

FIG. 7 is a rear elevation view thereof;

FIG. 8 is a perspective view of an alternate form of my design;

FIG. 9 is a side elevation view of the alternate form as seen from the right in FIG. 8;

FIG. 10 is a side elevation view of the alternate form as seen from the left in FIG. 8;

FIG. 11 is a top plan view of the alternate form;

FIG. 12 is a bottom plan view of the alternate form;

FIG. 13 is a front elevation view of the alternate form;

FIG. 14 is a rear elevation view of the alternate form; and, FIG. 15 is an enlarged cross section view common to both embodiments of the design and taken along lines 15—15 in FIGS. 2 and 11.
